UNITED STATES PATENT OFFICE.

ROBERT S. PELLETTE, OF KENNETT SQUARE, PENNSYLVANIA, ASSIGNOR TO AMERICAN ROAD MACHINERY COMPANY, INC., OF KENNETT SQUARE, PENNSYLVANIA, A CORPORATION OF DELAWARE.

ROAD MACHINE.

Application filed September 17, 1925. Serial No. 56,796.

My invention relates to an improvement in road machines and more particularly to an improved machine for grading roads.

In the grading of roads, whether on new construction or on repair of worn out or damaged roads, it is customary to utilize tools for rooting up or scarifying the surface and a blade for distributing and leveling off material.

Heretofore it has been customary to provide a machine equipped with a blade adapted to accomplish the distribution and levelling of material and to provide some other machine with the means for scarifying. As a result, the scarifying and distribution and levelling cannot be accomplished effectively in succession, it being necessary to first scarify and then distribute and level with the use of separate machines.

Now it is the object of my invention to provide a machine which will include, in its structure, both scarifying tools and a scraper blade so mounted as to be adaptable for use separately or simultaneously and which further will be so mounted as to enable them to be separately or simultaneously manipulated to the greatest advantage.

Further objects of my invention are to provide a machine of the character described, which will be of generally improved structure and which will be of a maximum durability and efficiency for the uses to which it is intended to be put.

Having now indicated, in a general way, the nature and purpose of my invention, I will proceed to a detailed description of a preferred embodiment thereof, with reference to the accompanying drawings, in which—

Fig. 1 is a side elevation of a road grading machine embodying my invention, with the scarifying tools and scraper bar in inactive position.

Fig. 2 is a plan view of the machine illustrated in Fig. 1, with parts omitted for clearness.

Fig. 3 is a sectional view on line 3—3, Fig. 1, with the scraper bar in active position.

Fig. 4 is a side view of the scarifying tools and scraper bar assembly in working position.

Fig. 5 is a plan view of the assembly shown in Fig. 4.

The machine embodying my invention comprises essentially a frame *a* supported on a front axle *b* and a rear axle *c*, upon which are mounted wheels *d*. The front axle is turnable relative to the frame through a fifth wheel *e* and vertical pivot *f*, while the rear axle may be turned relative to the frame or shifted laterally with respect thereto by manipulation of suitable mechanism, well known in the art, and controlled by the usual hand wheels *g* and *h*.

Mounted on the pivot *f* and extending rearwardly is a bracket *i*, upon which is rotatably mounted a bracket *j* secured to the forward end of a V-shaped draft member *k*. Connection between the bracket *j* and the bracket *i* is made through a coil spring *m* embracing bracket *i* and abutting against a collar *n* secured thereon, so that the draft on member *k* is through spring *m*. The draft member *k* is, it will be noted, turnable about pivot *e* and also about bracket *i*. Secured transversely of member *k*, adjacent its rear end, is an angle bar *o*, which is engaged adjacent each of its ends by the ends of links *p*, the other ends of which are secured to cranks *q* on the ends of shafts *r* adapted to be rotated by means of hand wheels *s* through worms and gears *t*. It will be observed that through manipulation of hand wheels *s* the member *k* may be tipped one way or the other through rotation about bracket *i*.

A link *u* is connected at one end to the bar *o* through an extension of its end through a slot *v*, and at its other end to a nut *w* in threaded engagement with a screw *x*, mounted transversely of frame *a* above bar *o*. Screw *x* is adapted to be rotated by means of a hand wheel *y* on a shaft *z* connected to a screw *x* through bevel gears 1. It will be observed that if hand wheel *y* be rotated, rotation of screws *x* will be effected and nut *w* will travel thereon, causing bar *o* and the rear end of member *k* to be moved laterally through rotation about pivot *e*. Guided by brackets 2, depending from member *k* and bar *o*, is a circle 3 having a gear 4 on its upper surface and provided with a series of spaced holes 5 adjacent its periphery, which elements form a turn table. A gear 6 on the end of a shaft 7 supported by member *k* meshes with gear 4 on circle 3 and may be actuated to rotate circle 3 by a

handle 8 on a shaft 9 connected to shaft 7 through a universal joint 10.

The circle may be retained in any adjusted position by means of a pin 11, passed 5 through suitable holes in one of the brackets 2 and one of the holes 5 in the circle.

Secured within the circle is a circular angle member 12 beneath which are secured transversely extending channel members 13, 10 one of which extends centrally of the circle 3 and is connected to bar 6 by means of a pivot pin 14, which, through the member 13, serves to support the circle clear of its guiding brackets 2. Adjacent the ends of member 13, which extend beyond the circle 15 3, and secured transversely thereof are a pair of angle bars 15, which, as will be observed, extend longitudinally of the machine.

20 To the sides of bars 15 to the rear of their centers are pivotally secured brackets 16, which are in turn secured to a scraper bar 17 adjacent its ends, as shown in Fig. 4. The brackets 16 are provided with a series 25 of holes 18, and links 19 are pivotally secured to the bars 15 adjacent their rear ends. The links 19 are adapted to be connected to the brackets 16 by means of pins 20 which may be passed through any one of 30 the holes 18 in the brackets. The links serve to brace the brackets and the scraper bar supported thereby in desired working position, as shown in Fig. 4. When, however, it is desired to render the scraper 35 inactive, it is lifted and the bracket secured directly to bars 15 by passing the pin 20 through the brackets and through holes 21 provided in the bars 15, as shown in Fig. 1.

A pair of brackets 22, similar to brackets 40 16, is pivotally secured to bars 15, ahead of their centers, and are connected by a transversely extending bar 23 of channel section. The sides of the bar 23 are notched at 45 intervals for the reception of picks or scarifying tools 24, which are clamped to the bar by means of notched shoes 25 and bolts 26. Links 27 are pivotally secured to bars 15, adjacent their forward ends, and are adapted to be connected to bracket 22 by pins 28 which are passed through one of a 50 series of holes 29 in the brackets. The links 27 serve to brace the brackets and bar 23 to retain the scarifying tools in adjustable working position, as shown in Fig. 4.

55 When, however, it is desired to render the scarifying tools inactive, the bar 23 is lifted and the brackets secured directly to bars 15 by passing pin 28 through the brackets and through holes 30 provided in bars 15, as shown in Fig. 1.

From the above description, the operation and advantage of the machine embodying my invention will, it is believed, be apparent.

60 It will be particularly noted that the

circle 3, supported from the draft member 6 and from which the blade 17 and scarifying tools 24 are supported, is movable laterally and also may be tipped, thus enabling all desired adjustment of the tools 70 and blade. It will be further noted that both the blade 17 and the scarifying tools 24 are supported from the same circle; however, being adjustable into various working positions or into inactive position 75 wholly independently of one another, thus enabling either the blade or the scarifying tools to be used independently or simultaneously, each having independent as well as common adjustability.

Having now fully described my invention, what I claim and desire to protect by Letters Patent is:

1. A tool support comprising a frame arranged to be supported from a road working machine, a cross-member on the frame, an annular support pivotally mounted on the cross-member, a cross-member connected to the annular frame on each side of the axis thereof, and a tool supporting member on 85 each side connected to the ends of the last mentioned cross-members.

2. A tool support comprising a frame arranged to be supported from a road working machine, a cross-member on the frame, an annular support pivotally mounted on the cross-member, a cross-member connected to the annular frame on each side of the axis thereof, a tool supporting member on each 95 side connected to the ends of the last mentioned cross-members, and other means on the frame for rotatably supporting the outer portion of the annual support.

3. A rotatable tool support for a road making machine, comprising a frame having 105 upper and lower annular flanges connected to each other by a web, the upper flange being arranged to engage guides in a supporting frame, transverse flanged supports connected to the lower flange, and longitudinally extending flanged tool supports connected to the ends of the transverse supports.

4. A rotatable tool support for a road making machine, comprising a frame having 115 upper and lower annular flanges connected to each other by a web, the upper flange extending outwardly while the lower flange extends inwardly, the upper flange being arranged to engage guides in a supporting frame, transverse supports connected to the lower flange, and longitudinally extending tool supports connected to the ends of the transverse supports.

5. A rotatable tool support for a road making machine, comprising a frame having 125 upper and lower annular flanges connected to each other by a web, the upper flange being arranged to engage guides in a supporting frame, transverse supports connected to the lower flange, longitudinally extending 130

tool supports connected to the ends of the transverse supports and means other than the guides for pivotally connecting the frame to a road making machine.

- 5 6. A rotatable tool support for a road working machine comprising an annular frame built up of two angle sections bent to circular form with their vertical flanges riveted to each other, the upper flange of one section extending outwardly and adapted to be engaged by supporting means on the road making machine, the lower flange of the other section extending inwardly, three channel shaped cross-bars having their webs connected to the lower flange, and a longitudinally extending tool supporting bar at 10 one section extending outwardly and adapted to be engaged by supporting means on the road making machine, the lower flange of the other section extending inwardly, three cross bars connected to the lower flange, and a longitudinally extending tool supporting bar at 15 side connected to the ends of the three cross-bars.

7. A rotatable tool support for a road

working machine comprising an annular frame built up of two angle sections bent to 20 circular form with their vertical flanges riveted to each other, the upper flange of one section extending outwardly and adapted to be engaged by supporting means on the road making machine, the lower flange of the other section extending inwardly, three channel shaped cross-bars having their webs connected to the lower flange, and a longitudinally extending tool supporting bar at 25 side connected to the ends of the three cross-bars.

In testimony of which invention, I have hereunto set my hand, at Kennett Square, Pa., on this 10th day of Sept., 1925.

ROBERT S. PELLETTE.
